SLEEVE INSERTER ADAPTER

Clark H. Landis, Bowling Green, Ohio

Application July 3, 1947, Serial No. 758,735

3 Claims. (Cl. 29—283)

1.

This invention relates to improvements in sleeve inserter apparatus.

An object of the invention is to provide an improved sleeve inserter adapter for inserting sleeves or linings into the cylinders of internal combustion engines or into other cylinders.

Another object of the invention is to provide an improved sleeve inserter adapter including an associated hydraulic cylinder and piston device for positively and forcibly inserting a sleeve or lining into a cylinder of an internal combustion engine, the same including positive guiding means whereby the sleeve will be accurately inserted and positioned within the cylinder.

A further object of the invention is to provide an improved sleeve inserter adapter including an associated hydraulic cylinder and piston device, with means for accurately guiding a sleeve or lining into a cylinder, and further means for adapting sleeves longer than their receiving cylinders to accurately position the same in said cylinders.

A still further object of the invention is to provide an improved sleeve or lining inserter adapter comprising a recessed body adapter and an apertured guide disk associated therewith and having guiding means and resilient means for normally holding said body and disk in spaced relation.

Another object of the invention is to provide an improved sleeve or lining inserter adapter which will be highly efficient in operation, and relatively inexpensive to manufacture and produce.

Other objects will appear as the description proceeds.

In the accompanying drawings which form a part of this application;

Figure 1 is a side elevation of the hydraulic power cylinder showing the piston and piston rod dotted in position therein for operating the sleeve adapter inserter;

Figure 2 is a vertical sectional view through the hydraulic power cylinder and piston, showing the same in operative position attached to the sleeve inserter adapter ready to insert a sleeve within the cylinder of an internal combustion engine;

Figure 3 is a sectional view taken on the line 3—3 of Figure 2; and

Figure 4 is a plan view of the improved guide disk.

Like characters of reference are used throughout the following specification and the accompanying drawings to designate corresponding parts.

2.

In carrying out the invention, there is provided and illustrated an internal combustion engine cylinder block generally designated by the reference numeral 1 having a cylinder 2 with water passages 3 formed about said cylinder for cooling the same.

A hydraulic power cylinder 4 is closed at its lower end by means of a head member 5 having an annularly disposed peripheral flange 6 formed about the edge thereof. The hydraulic power cylinder is externally threaded, as at 7, on its upper end and is adapted to receive a screw cap closure member 8 upon its upper end.

A pair of oppositely disposed fittings or connections 9 and 10 are adapted to extend through the lower wall of the hydraulic power cylinder 4 for respectively connecting with a source of oil or other desired fluid under pressure (not shown) and with a pressure gauge (also not shown).

A depending neck 11 is formed integrally with and centrally of the lower surface of the head member 5, and a vertical bore 12 is formed completely through said head member and neck.

A piston, generally designated by the reference numeral 13, is reciprocably disposed within the hydraulic power cylinder 4 and comprises the spaced leather cups 14 and 15 which are separated by the metal disk 16 and secured in position by the metal disks 17 and 18 upon the threaded upper end 19 of the piston rod 20 which slidably extends through the vertical bore 12 in the head member 5 and neck 11.

The piston rod 20 is of sufficient length to extend through the engine cylinder 2 and through the metal sleeve or lining 21 before it is inserted within the engine cylinder 2. The lower end of the piston rod 20 is threaded, as at 22 and is adapted to receive a securing nut 23 threadable thereon.

The metal sleeve or lining 21 is formed about its upper end with a laterally extending peripheral positioning flange 24 which will seat against the lower surface of the head member 5 when in position for insertion within the engine cylinder 2, said flange 24 being adapted to be received within the annular peripheral groove or seat 25 formed in the engine block 1 about the upper end of the cylinder 2.

Very often a metal sleeve or lining 21 is somewhat longer than the length of the engine cylinder 2 into which it is to be inserted, and will extend below the same when inserted within the cylinder.

To provide for these variations in the lengths of the metal sleeves or inserts 21, there is provided a cylindrical adapter or body 26 formed

of metal or any other suitable material, having a cylindrical seat or recess 27 formed in its upper surface of a similar diameter to the diameter of the engine cylinder 2. A peripheral upstanding supporting flange 28 is formed about the seat of the adapter body 26 with the opening of the cylinder 2 and said recess 27 being in vertical and axial alignment. A centrally disposed vertical bore 29 is formed through the cylindrical adapter body 26 to permit the piston rod 20 to slide freely therethrough as the sleeve or lining 21 is being inserted within the engine cylinder 2. Three equally spaced, circumferentially disposed, threaded bores 30, 31 and 32 are formed through the adapter body 26 in circumferential arrangement being disposed between wells or seats 33, 34 and 35, adapted to receive the three coil springs 36, 37 and 38.

A guide disk 39 is provided with a central vertical bore 40 through which the piston rod 20 will pass, and with three circumferentially disposed bores 41, 42 and 43 extending through the disk for receiving the three guide pins 44, 45 and 46 which are headed, as at 47, and are screw-threaded, as at 48, on their lower extremities for threading through the threaded bores 30, 31 and 32 in the adapter body 26.

It will therefore be seen from Figure 2 of the drawings that the coil springs 36, 37 and 38 which are seated in the wells 33, 34 and 35 will support the disk 39 partially within the cylindrical seat or recess 27 formed in the upper surface of the adapter body 26 and partially within the hollow cylinder or wall 2, while the three guide pins 44, 45 and 46 will guide the vertical movement or adjustment of said guide disk 39. The guide pins 44, 45 and 46 being externally threaded through the threaded bores 41, 42 and 43 through the adapter body 26 will permit of adjustment of the guide disk 39 with respect to said cup-shaped body 26.

From the foregoing description, the mode of operation will be as follows: The hydraulic power cylinder 4 with its piston supporting piston rod extending through the head 5 and neck 11 with the packing gland 49 threaded about the lower end of said neck 11 is placed in position for the sleeve or lining 21 to be telescoped over the lower end of the piston rod 20 to seat on the head 5, and the piston rod will be inserted downwardly through the cylinder 2 in the engine block 1, as clearly illustrated in Figure 2 of the drawings. With the piston 13 near the bottom of the hydraulic power cylinder 4, the lower end of the piston rod 20 will extend considerably below the lower end of the engine cylinder 2, and the guide disk 39 and cylindrical adapter body 26 will be telescoped over the lower end of the piston rod with the upstanding flange 28 in contact with the lower surface of the block 1, being secured against a piston rod carried abutment means, herein shown as the nut 23. In this position, the guide disk will be resiliently held in elevated position partially within the recess 27 in the adapter body 26 and partially within the cylinder 2. Hydraulic fluid under pressure will be admitted through the connection 9 to the interior of the hydraulic power cylinder 4 below the piston 13 and the piston will be stationary, since the piston rod 20 is firmly anchored at its lower end beneath the bottom of the engine block 1. Therefore, as the fluid under pressure is admitted below the piston within the cylinder 4, the cylinder will be forced downwardly, thereby causing the head 5 thereof to force the sleeve or

lining 21 downwardly within the engine cylinder 2 until the annular peripheral flange 24 on said sleeve is received within the annular peripheral seat 25 formed in the engine block 1 about the upper end of the cylinder 2. As the sleeve or lining 21 descends, and should the same be longer than the cylinder 2, its lower end will engage the guide disk 39 and force the same downwardly against the tension of the three-coil spring 38, thereby guiding and supporting the lower end of said sleeve or lining 21 until it is firmly and fixedly positioned within the cylinder 2.

From the foregoing description, it will be apparent that there has been devised and provided a highly efficient form of sleeve inserter adapter which will be relatively inexpensive to manufacture and produce.

While the preferred embodiment of the instant invention has been illustrated and described, it will be understood that it is not intended to limit the scope of the invention thereto, as many minor changes in detail of construction may be resorted to without departure from the spirit of the invention.

Having described the invention, what is claimed as new is:

1. An adapter for mechanism used to insert sleeves into cylinders of internal combustion engines, said mechanism including a piston rod adapted to transmit axial thrust, an abutment detachably positioned on said piston rod and adjustable therealong adjacent one end thereof, a centrally apertured cup-shaped member on said piston rod, said member having the lower side of its body engaged by said abutment and its upper side forming a peripheral upstanding flange about a recess therein, said flange adaptable to engage the engine about the lower end of a cylinder therein with said recess providing a continuation of said cylinder, a guide disk slidably mounted on said piston rod and shiftable in and out of said cylinder to and from said recess, and a concentric series of guide pins and springs alternately positioned about said piston rod and disposed between said disk and the cup-shaped member, said pins adjustable in said member and provided with means limiting the movement of said disk out of the recess with said springs normally urging said disk toward such limit.

2. An adapter for mechanism used to insert sleeves into the cylinders of internal combustion engines, said mechanism including a piston rod adapted to transmit axial thrust; an abutment detachably positioned on said piston rod adjacent one end thereof, a centrally apertured cup-shaped member on said piston rod, said member having the lower side of its body engaged by said abutment and its upper side forming a peripheral upstanding flange about a recess therein, said flange adaptable to engage the engine about the lower end of a cylinder therein with said recess providing a continuation of said cylinder, a guide disk slidably mounted on said piston rod and shiftable in and out of said cylinder to and from said recess, a guide pin for said disk extending from said cup-shaped member, and means carried by said pin for limiting the movement of said disk as to said recess.

3. An adapter for mechanism used to insert sleeves into the cylinders of internal combustion engines, said mechanism including a piston rod adapted to transmit axial thrust, an abutment detachably positioned on said piston rod adjacent one end thereof, a centrally apertured cup-shaped

member on said piston rod, said member having the lower side of its body engaged by said abutment and its upper side forming a peripheral upstanding flange about a recess therein, said flange adaptable to engage the engine about the lower end of a cylinder therein with said recess providing a continuation of said cylinder, a guide disk slidably mounted on said piston rod and shiftable in and out of said cylinder to and from said recess, a guide pin for said disk extending from said cup-shaped member, means carried by said pin for limiting the movement of said disk as to said recess, and spring means between said disk and the bottom of said recess normally urging said disk to the limit allowed by said pin carried means.
